US00D712930S

(12) **United States Design Patent**
Lee et al.

(10) **Patent No.:** US D712,930 S
(45) **Date of Patent:** ** Sep. 9, 2014

(54) **ELECTRONIC DEVICE**

- (71) Applicant: **Samsung Electronics Co., Ltd.**, Suwon-si (KR)
- (72) Inventors: **SangChul Lee**, Namyangju-si (KR); **Sangmin Hyun**, Seoul (KR); **Hoseong Seo**, Suwonsi (KR); **Shiyun Cho**, Anyangsi (KR)
- (73) Assignee: **Samsung Electronics Co., Ltd.**, Suwon-si (KR)

(**) Term: **14 Years**

(21) Appl. No.: **29/459,665**

(22) Filed: **Jul. 2, 2013**

(30) **Foreign Application Priority Data**

Jan. 4, 2013 (KR) 30-2013-0000676

(57) **CLAIM**

The ornamental design for an electronic device, as shown and described.

DESCRIPTION

FIG. 1 is the front/right-side/top perspective view of an electronic device showing our new design; FIG. 2 is the front elevational view thereof; FIG. 3 is the rear elevational view thereof; FIG. 4 is the left-side elevational view thereof; FIG. 5 is the right-side elevational view thereof; FIG. 6 is the top-side plan view thereof; and, FIG. 7 is the bottom-side plan view thereof.

The broken lines in the drawings indicate unclaimed portions of the design and form no part of the claimed design.
